FACE PLATE FOR GOLF CLUBS

Lynn A. Davis, Jr., Springfield, Mass., assignor to A. G. Spalding & Bros., Inc., Chicopee, Mass., a corporation of Delaware

Filed Feb. 4, 1959, Ser. No. 54,453

Term of patent 7 years

(Cl. D34—5)

Fig. 1

Fig. 2 is a front view of the face plate; and
Fig. 3 is an end view of the face plate.

The dominant features of my design reside in the portions shown in full lines.

The dotted head is shown to disclose the environment of the face plate, said face plate being characterized by a V-shaped element of contrasting color disposed between the top and bottom thereof and extending for substantially the width thereof.

I claim:

The ornamental design for a face plate for golf clubs, as shown and described.
